UNITED STATES PATENT OFFICE.

JOHN E. POTTER, OF SAPULPA, OKLAHOMA.

MEANS FOR SEVERING AND DISTRIBUTING MOLTEN MATERIAL.

1,317,176.

Specification of Letters Patent. Patented Sept. 30, 1919.

Application filed April 16, 1918. Serial No. 228,852.

To all whom it may concern:

Be it known that I, JOHN E. POTTER, a citizen of the United States, residing at Sapulpa, in the county of Creek and State 5 of Oklahoma, have invented a new and useful Improvement in Means for Severing and Distributing Molten Material, of which the following is a full, clear, and exact description, reference being had to the accompanying drawings, forming part of this 10 specification, in which—

Figure 1 is a plan view of certain portions of a glass working machine embodying my invention.

15 Fig. 2 is a section on the line II—II of Fig. 1.

Fig. 3 is a top plan view of the carrier for the guiding and distributing members, and

20 Figs. 4, 5, 6 and 7 are diagrammatic views illustrating the operation in different stages.

My invention is designed to provide simple and effective means for severing or separating a continuously flowing stream of 25 molten material, such as glass, and distributing the severed portions successively into a series of receptacles, such as molds. A further, and more specific object is to accomplish this result without the necessity 30 for at any time supporting the flowing stream above the point of separation or severance. A still further object is to enable the severing to be done while the machine is in motion. My invention also provides means for accomplishing the above 35 stated objects which, when applied to a glass forming machine, will be out of the way of the operations performed upon the glass after it enters the forming receptacles 40 or molds.

The nature of my invention will be best understood by reference to the accompanying drawings in which I have shown a preferred embodiment thereof, and which will 45 now be described, it being premised, however, that various changes can be made in the details of construction, arrangement and combination of the parts, without departing from the spirit and scope of the invention as defined in the appended claims. 50 Also that the invention is capable of application to various other forms of glass working machines.

In these drawings the numeral 2 designates a vertical post or column upon which

is mounted a rotating table 3 of a glass working machine, the table being rotated by any suitable gearing, such as indicated at 4. Supported upon the table 3 are a plurality of mold vessels. In the drawing I 60 have shown the table as having ten of these vessels which I have designated, respectively as A, B, C, D, E, F, G, H, I, and J.

5 designates a sleeve member which is secured to the table 3 to rotate therewith 65 and which, at its upper portion, is provided with a horizontal extension 6. Formed in the upper surface of this extension 6 is a plurality of radial grooves 7. In each of these grooves is a slidably mounted

bar 8 which, at its outer end, carries a glass guiding and distributing member. These members also act as cutting or shear elements. Each of these members consists of a short upper horizontal heel portion 9 and a downwardly and laterally directed

guiding and distributing portion 9^a, which is formed with a gutter or trough 9^b. The edge 9^c formed at the junction of the outer surface of the portion 9^a with the upper surface of the portion 9, constitutes a shearing or cutting edge, which is designed to co-operate with the cutting edge of a single fixed shear member 10 secured to the upper frame member 11, which is in turn

fixed to the post or column 2. The rear end face of each heel portion 9 is preferably ground vertically, as indicated at 9^d. One of the guiding and distributing members is provided for each mold vessel; and each

of these members is curved so that when in operative position its center line will be directly over the center line of rotary movement in the mold vessels. As these members rotate with the table in fixed relation to the molds, so far as rotary movement is concerned, they are moved radially into and out of operative position by suitable means. In the arrangement shown, such means consists of a cam groove 12 formed in the under

side of the frame member 11 and engaged by an anti-friction roller 13 on each of the bars 8. The form of this cam groove is best shown in Fig. 1 and this figure also clearly illustrates the movement of the said

members into and out of operative positions as they approach and leave the mold charging station of the machine.

14 designates any suitable source of supply, from which a stream of molten glass 110

may continuously flow, such as a melting tank, furnace or pot. The fixed shear member 10 is located adjacent to this flowing stream, as best shown in the diagrams on Sheet 3 of the drawings. This member may, if desired, be water cooled, as indicated at 15 to prevent sticking of the glass thereto. The operation is clearly shown in the diagrams.

10 Referring first to Fig. 4, the mold A has been filled; and the mold B is directly underneath the charging source and is directly receiving therein the flowing stream of glass, the table 3 moving either continuously 15 or intermittently in the direction indicated by the arrows.

In Fig. 5 the continued movement of the table has brought one of the guiding and distributing members below the flowing stream of glass, and its gutter portion 9^a is directing this flowing stream laterally into the mold B. In Fig. 6 the said guiding and distributing member has been brought into shearing relation to the fixed 25 shear element 10 and the flowing stream has been sheared, the portion of the glass below the point of separation continuing to flow into the mold B. When the parts reach the position shown in Fig. 7, substantially all 30 the glass has flowed into the mold B, and the next succeeding mold C is brought directly underneath the flowing stream.

It will be understood that the molds are successively filled in this manner. The 35 lateral extension of each of the guiding and distributing members is sufficient to direct the glass into its corresponding moving mold until such time as the next filling mold has been brought into position to receive 40 the stream. In this manner there is practically no interruption of the flowing stream, and it is unnecessary to provide any support to that portion of the stream above the point of severance. The severing is effected 45 while the machine is in operation. With a uniform stream of molten material and a uniform movement of the table, the molds will, therefore, receive measured charges substantially uniform in volume. The vertical grooves 9^a in the heel portions 9, provide for the continued flow of the glass after 50 each severing operation, and prevent temporary support of the flowing stream on such heel portions.

55 It will be further noted from Fig. 1 that the cam groove 12 does not act to advance the guiding and distributing members until they respectively approach the charging station; and that said members are retracted 60 shortly after passing such station. In their retracted positions they are entirely out of the way of the performance of subsequent operations upon the glass in the molds.

My invention is capable of being applied to various kinds of glass forming ma-

chines, is simple in its construction and positive in its operation, and forms a simple and effective means for the designed purposes.

I claim:

1. In apparatus of the character described, 70 the combination with a receptacle, and means for moving the same below a source of molten material, of a guiding and distributing member rotatable with said receptacle and arranged to receive and direct 75 the glass laterally from the source into the receptacle together with means for severing the flowing stream, the parts being so arranged that the front end of the severed stream is unsupported by the guide while 80 the tail end of the severed stream is directed into the receptacle by the guide; substantially as described.

2. In apparatus of the character described, 85 the combination with a receptacle, and means for moving the same below a flowing stream of molten material, of a guiding and distributing member rotatable with the mold, said member having a laterally and downwardly inclined flow channel together with 90 means for severing the flowing stream, the parts being so arranged that the front end of the severed stream is unsupported by the guide and distributing member while the tail end of the severed stream is directed 95 into the receptacle by the inclined flow channel; substantially as described.

3. In apparatus of the character described, 100 the combination with a receptacle, and means for moving the same below a flowing stream of molten material, of a guiding and distributing member rotatable with the mold, said member having a laterally and downwardly inclined flow channel, and also 105 acting as a cutting element, the parts being so arranged that the front end of the severed stream is unsupported by the guide while the tail end of the severed stream is directed into the receptacle by the inclined flow channel; substantially as described.

4. Means for separating a continuously flowing stream of molten material and distributing the same into receptacles, comprising a fixed severing device, and a plurality of movable coöperating severing devices, the latter having means below the point of severance for directing the molten material into a receptacle, said severing devices being constructed and arranged to sever the flowing stream at times when its portion below the point of severance is supported on one of the movable severing devices while the following portion is unsupported by the severing device; substantially 115 as described.

5. In apparatus of the character described, the combination of a plurality of receptacles and means for moving the same in succession below a constantly flowing stream of molten material, a single fixed cutting de- 120 125 130

vice adjacent to said flowing stream, and a plurality of moving coöperating devices, one for each of said receptacles, each of said devices having means below the point of severance for supporting and directing the tail end of the material into a corresponding receptacle while the following portion is unsupported; substantially as described.

6. In apparatus of the character described, the combination of a plurality of receptacles and means for moving the same in succession below a constantly flowing stream of molten material, a single fixed cutting device adjacent to said flowing stream, and a plurality of moving coöperating cutting devices, one for each of said receptacles, each of said devices having means below the point of severance for supporting and directing the tail end of the material into a corresponding receptacle while the following portions of the material is unsupported, said devices being movable with the molds; substantially as described.

7. In apparatus of the character described, the combination of a rotatable carrier having a plurality of receptacles, means for delivering a constantly flowing stream of molten material below which the said receptacles move in succession, a fixed shear element adjacent to the flowing stream, a plurality of shear elements arranged to rotate with the receptacles, there being one for each receptacle to be filled, and each of said elements having a downwardly and laterally inclined guiding and distributing portion, together with means for moving the last

named elements into and out of operative position as they approach and leave the receptacle filling stations, said shear elements being constructed and arranged to sever the flowing stream at times when its portion below the fixed shear element is supported on one of the movable shearing elements and the following portion is unsupported by a shearing element; substantially as described.

8. In apparatus of the character described, the combination with a fixed shear element, of a movable shear element, the latter comprising a relatively short horizontal portion, and a downwardly and laterally inclined trough portion, the edge of the element formed at the junction of the two portions constituting a shearing edge, the parts being so arranged that the front end of the severed stream is unsupported by the trough portion while the tail end of the severed stream is directed into a receptacle by the trough; substantially as described.

9. In apparatus of the character described, the combination with a plurality of movable receptacles, of a glass guide and distributing element arranged to move with each receptacle, together with means for severing the flowing stream, the parts being so arranged that the front end of the severed stream is unsupported by the guide while the tail end of the severed stream is directed into a receptacle by its guide.

In testimony whereof, I have hereunto set my hand.

JOHN E. POTTER.
